UNITED STATES PATENT OFFICE.

MANSFIELD M. WEST, OF CLEVELAND, AND BRENNAN B. WEST, OF CLEVELAND HEIGHTS, OHIO, ASSIGNEES TO THE UNIVERSAL SHOE PLATE COMPANY, OF CLEVELAND, OHIO, A CORPORATION OF OHIO.

LAST.

Application filed May 7, 1923. Serial No. 637,134.

To all whom it may concern:

Be it known that we (1) MANSFIELD M. WEST, (2) BRENNAN B. WEST, citizens of the United States, residing at (1) Cleveland, (2) Cleveland Heights, in the county of Cuyahoga and State of Ohio, have invented a certain new and useful Improvement in Lasts, of which the following is a full, clear, and exact description, reference being had to the accompanying drawings.

The primary purpose of our invention is to provide a last and stand for supporting shoes of practically any size while applying shoe plates or protectors to the soles and heels thereof, and which is convertible from a comparatively flat bottom last to one having a high arch so as to accommodate both relatively flat shoes and those having high heels and consequently high arches.

Again, and more generally, our aim is to provide an outfit particularly for home use, of as few parts as possible which will support shoes of practically all sizes and styles with the security necessary for applying shoe plates to the soles and heels thereof.

While intended for use especially in applying shoe plates, the invention has, of course, a much wider field of utility and may be used under any circumstances where ordinary lasts of similar size are employed.

More specifically stated, our invention has for its objects to provide a well proportioned last and stand, combined in an integral unit, and of a size and shape that will render it suitable for supporting shoes of various sizes, as, for example, children's comparatively flat bottom shoes while applying plates to either the soles or heels thereof, or girls' and boys' and men's and women's shoes while applying plates, especially to the heels thereof, it being necessary, of course, to shift the position of the shoe on the last until the part of the sole or heel to which the plate is to be attached is properly supported; and to provide an attachment or so-called toe extension which may be readily applied to the last thereby to convert it into one having a high arch and narrow toe to better adapt it to the styles of women's high heel shoes, the toe of the original last, through such conversion, becoming the heel of the high arch last

so that the assembly is better proportioned 55 and the pedestal or stand more centrally located with respect to the high arch last thereby to better balance the structure and prevent interference with the shifting of a shoe thereon to the desired position. 60

Further objects are to provide a simple and inexpensive yet very substantial and practically indestructible device of the aforesaid character possessing the foregoing features and which is particularly convenient of use. 65

The present preferred embodiment of our invention is illustrated in the accompanying drawing wherein Fig. 1 is a side elevation, and Fig. 2 is a plan view of the complete device; Figs. 3 and 4 are, respectively, a side elevation and plan view of the combination last and stand with the toe extension removed; and the respective Figs. 5, 6 and 7 are a side elevation, top plan, and 75 bottom plan of the toe extension.

Cast or otherwise produced as a single unit, is the combination last and stand shown alone in Figs. 3 and 4. This unit comprises a comparatively flat bottom last 1 which is supported by a pedestal 2 a desirable distance above a base 3 which is shown as provided with notches 4 for the accommodation of suitable fastening means, such as screws, for securing the device to a 80 support. Between the sole and heel, the body portion of the last is provided with recesses or sockets 5 which open upwardly and are shown as separated by a rib 6 that connects the sole and heel portions and 85 imparts the required strength to the structure. 90

It will be readily understood how a shoe may be slipped over the last 1 in inverted position and supported so that shoe plates or protectors may be driven into the sole or heel thereof. If the shoe is small enough to fit the last 1 it will be properly supported at both toe and heel. A larger shoe, however, must be shifted forwardly if it is the intention to apply a plate to the heel thereof, or rearwardly if it is the desire to apply a plate to the sole or toe. It is found that a small last of the style illustrated will properly support shoes having comparatively flat bottoms throughout a very 105 wide range of sizes. 100

To adapt the last to what are known as high arch shoes—that is, shoes having high

heels, such as French heels, and consequently high arches—a toe extension, designated 8, is employed which has lugs 9 designed to fit within the sockets 5, and an abutment portion 10 which bears upon the heel of the last 1 so that the toe extension is very firmly supported against downward movement. In thus converting the original last into a high arch last, the toe of the former last becomes 10 the heel of the high arch last. This is particularly desirable not only because the toe of the former last bears a proper relation to the sole portion of the toe extension 8, but the arrangement somewhat centralizes the 15 stand or pedestal with respect to the high arch last and thus permits a shoe to be shifted to a greater extent than if the stand or pedestal was closer the heel.

It will be seen from the foregoing that our 20 invention provides a very simple last outfit of only two parts which adapts itself to shoes of practically all sizes and styles.

Having thus described our invention, what we claim is:

- 25 1. In combination, a comparatively flat bottom last, and an extension member adapted to be applied thereto in such relation as to produce a high arch last with the heel portion thereof constituted of the toe portion of the first mentioned last.
- 30 2. In combination, a comparatively flat bottom last supported adjacent its heel by a pedestal, and an extension member adapted to be applied to said last in such relation 35 as to produce a high arch last the heel por-

tion whereof is constituted of the toe portion of the first mentioned last and wherein the pedestal is properly positioned with respect to the high arch last.

3. In combination, an integral unit comprising a stand and a complete comparatively small last, and an extension member adapted to be applied to said last to convert it into a larger last that is reversed with respect to the former last, the toe portion of the smaller last becoming through such conversion the heel portion of the larger last.

4. In combination, a comparatively flat last having a rounded toe, and a toe extension member adapted to be applied to said last so as to project beyond the heel thereof, said toe extension member being shaped to produce, with the former last, a high arch last having as its heel the toe portion of the first mentioned last.

5. In combination, an integral unit comprising a comparatively flat bottom last having a rounded toe and a pedestal supporting said last and joining the same adjacent its heel, and a toe extension member adapted to be applied to said last so as to project beyond the heel thereof, said member being so shaped as to produce, with the former last, a high arch last having as its heel the toe portion of the first mentioned last.

In testimony whereof, we hereunto affix our signatures.

MANSFIELD M. WEST.
